KNITTING MACHINE AND METHOD

Harry Avery Raynor, Wollaton Park, Nottingham,
EnglandOriginal application February 14, 1936, Serial No.
63,925, now Patent No. 2,108,925. Divided and
this application April 30, 1937, Serial No.
140,020. In Great Britain February 15, 1935

3 Claims. (CL. 66—9)

This invention is for a knitting machine and a method of machine knitting and the invention relates to the production of that type of fabric embodying one or more thread bars, other than 5 the stitch thread or threads, extending weft-wise of the fabric, i. e. in the direction of the stitch courses, and anchored in the fabric by stitch loops.

Heretofore a knitted fabric of the above type 10 has been proposed embodying a transversely extending strand or plurality thereof locked in the fabric by loops of the fabric extending through the strand or each of same. In this proposed fabric, however, the transversely extending 15 strand or each strand through which the fabric loops pass is constituted by a single thread such as a wrapped elastic thread individually introduced and locked in the fabric, and in the production of the fabric on a circular knitting machine only one strand is fed to the machine.

A characteristic feature of the fabric made by the exercise of the present invention consists in a weft-wise extending bar or bars each of which embodies a plurality of cores, pillars or strands 25 extending alongside each other and so connected as to be simultaneously introduced into the fabric as a composite bar or braid and anchored in a fabric by loops which pass between said cores, pillars or strands. By providing 30 a plural core or plural stranded weft bar in lieu of a single strand weft, it will be appreciated that the production of the fabric is considerably facilitated, as any difficulty experienced in causing a needle and stitch loop to pierce a single 35 strand, and particularly the encircling covering of a single elastic or other thread, is eliminated, it being a matter of comparative ease to pierce a composite weft bar or braid between the cores or strands. Additionally, the passage of loops between the cores or strands of a composite weft 40 provides a more secure and positive anchorage of the weft in the fabric.

The present invention provides a knitting machine having hooked needles, means for feeding knitting thread thereto, means for operating said needles to knit loops of said thread, means for feeding a weft thread to the needles, means for locating said weft thread below the points of the needle hooks, means for causing said points to pierce said weft thread, means for clearing said pierced weft thread over the bends of the hooks of the needles that pierce it onto the stems of said needles, and means for operating said weft-trans- 45 fixing needles to take knitting thread and to draw

loops thereof through the pierced weft thread and to cast off the latter in knitting.

The invention is particularly applicable to elastic knitted fabrics, i. e. fabrics including elastic threads; and in this connection the aforesaid composite weft bar or each or selected of same secured in the fabric may embody a plurality of elastic strands extending alongside each other and suitably bound together, one or more of said elastic strands being anchored by stitch loops 5 of one stitch course and another or others by loops of a succeeding course.

For the purpose of more fully describing the nature of this invention reference will now be made to the accompanying drawings, wherein:— 10

Fig. 1 is a face view of a portion of rib knitted fabric according to this invention.

Fig. 2 is a section through the fabric.

Fig. 3 is a face view of a modified fabric.

Fig. 4 is a section of the fabric shown in Fig. 3. 20

Figs. 5 to 14 inclusive are detail views illustrating successive steps in the production of the fabric shown in Figs. 1 and 2.

Fig. 15 is an elevational view of part of a circular knitting machine for producing the fabric. 25

Fig. 16 is an enlarged detail view of part of the machine shown in Fig. 15 but looking at same from the opposite side.

Fig. 17 is a detail view showing one method of making a dual stranded weft for incorporating 30 in the knitted fabric.

By way of example, the invention will now be described as applied to a rib knitted fabric, e. g. a one-and-one rib having incorporated therein weftwise extending elastic thread bars 1. Each of the said weft thread bars 1 may consist of two rubber strands or threads 2 each wrapped with one or more layers 3 of cotton or other desired yarn in the well-known manner, and the two wrapped rubber strands 2 being connected or bound together alongside each other so as to constitute a narrow braid, the covered elastic strands 35 constituting longitudinal pillars in said braid. This braided weft 1 is so incorporated in the rib fabric that one of the covered elastic strands or pillars 2 extends between and is gripped between the front stitch loops 4 and rear stitch loops 5 of one stitch course, while the other covered elastic strand or pillar of the same braided weft extends between and is gripped between the front 40 and rear stitch loops 4 and 5 of the next succeeding stitch course; the stitch loops at one side of the fabric, that is to say either the front loops 4 or rear loops 5 passing through the braided weft 1 between the said elastic strands or pillars 2 so 45

50

55

55

as positively to anchor the weft from displacement in the fabric.

The above-described fabric can be produced on any suitable type of rib knitting machine, and by way of example the production will now be described of a fabric according to Figs. 1 and 2 on a circular rib knitting machine, reference being made to Figs. 5 to 14 of the drawings. For convenience of description the operation of a single cylinder needle 6 and its co-operating dial needle 7 is referred to. Let it first be assumed that the cylinder needle 6 and the dial needle 7 have been retracted to the knock-over position with the last made stitch loops 8 and 9 carried in their hooks (Fig. 5); the cylinder needle 6 is now projected to a tucking height with the stitch loop 8 over the latch, the dial needle 7 being retracted (Fig. 6). The cylinder needle 6 during the lowering thereof is now brought round into engagement with a toothed or tricked rotatably mounted wheel or disc 10 which is formed at its periphery with a horizontal channel 12 through which the dual stranded elastic braid 1 is fed, said braid being fed horizontally beneath the hook 11 of the cylinder needle 6 in such a manner that the tip or point of the hook is caused during the continued downward movement or retraction of the needle to pierce the braid between the two elastic strands or pillars 2 thereof (Fig. 7). As the braid 1 is drawn by the needle hook 11 out of the channel 12 in the member 10 said braid is brought into a position with the two strands 2 thereof located vertically one above the other (Fig. 8), and the needle 6 then passes beneath the periphery of a horizontal rotary disc or the like 13 which acts on the dual stranded braid 1 to press one of the strands thereof over to the back of the needle hook and bring the pressed over strand of said braid above the loop 8 (Fig. 9). The cylinder needle 6 and dial needle 7 are now simultaneously projected to a thread feeding position, and in doing so the stitch loop 8 on the cylinder needle together with the dual stranded braid 1 is cleared below the cylinder needle latch, and the stitch loop 9 on the dial needle is also cleared behind the dial needle latch, and a new thread 14 is fed to both needles. The cylinder needle 6 is now retracted to the knock-over position and in so doing a loop 15 formed from the thread 14 is drawn through the old loop 8 and through the braid 1 midway in its width between the elastic strands 2, said braid 1 being thereby knocked over with the old loop 8 (Fig. 11). Following this the old loop 9 is knocked over from the dial needle 7 and a new loop 16 is drawn thereby from the thread 14 (Fig. 12). The two needles 6, 7 are now simultaneously projected to clear the last formed loops 15 and 16 and receive further thread 17 (Fig. 13), and said needles are operated in the customary manner to form further stitches from the last fed thread (Fig. 14).

By the above-described operation it will be seen that one of the strands 2 of the dual stranded braid 1 becomes embraced between stitch loops produced on the cylinder and dial needles, that is to say between the front and rear stitch loops of the fabric, and the second strand of the braid is so located as to become embraced between the cylinder and dial stitches produced at the next succeeding course; it being understood that at said second course the dual stranded braid is not fed to the needles. Thus it will be appreciated that the two strands 2 of the braided weft 1 are embraced in succeeding stitch

courses, the cylinder needle stitch loops being drawn through the braid between the strands thereof so as positively to lock the braid in position.

By feeding the dual strand braid at alternate courses, that is to say by causing the needles to pierce said braid at alternate courses, an elastic strand is incorporated in each successive course of stitches as before described. If desired, however, the stitch courses embodying the braided weft may alternate with other courses devoid of weft. The weft 1 when incorporating elastic threads may be fed to the needles under suitable tension and means are provided for guiding the weft to the needles so as to ensure said needles piercing the weft between the elastic strands thereof.

In Figs. 15 and 16 is illustrated a part of a circular knitting machine showing more clearly how the dual stranded braid is fed to the cylinder needles. The braid 1 is drawn from a suitable rotatably mounted supply 18 and passed through a guide 19 and between the circumferential faces of a pair of truncated conical feeding rollers 20 resiliently pressed together by a spring 21 or other suitable means. The speed at which the braid 1 is fed to the machine can be adjusted as required by moving said braid upwards or downwards between the rollers 20 so as to contact with the varying diameters of said rollers, and this may be accomplished by imparting rotation to a screw-threaded rod 22 on which is mounted an arm 23 retained from rotation and carrying the guide 19, the rotation of the screw 22 traversing said guide arm 23 up or down as required. The braid 1 after passing between the feed rollers 20 enters a flat channel 24 of a fixed guide member 25, which channel 24 brings the braid into position with the two strands 2 thereof horizontally disposed, and from this channel 24 the braid is guided into the horizontal channel 12 at the periphery of the aforesaid rotatably mounted toothed or tricked wheel 10, and the rotation of said wheel may be effected by the needles coaxing with the teeth or tricks thereof. This toothed and channelled wheel 10 serves to feed the dual stranded braid 1 beneath the hooks of the descending needles and positively locate and hold said braid in the correct position for ensuring that the points of the needle hooks successively pierce the braid midway in its width, i. e. between the strands 2; said braid being held up against the needle by which it is pierced. As the needles leave the teeth or tricks in the wheel 10 the braid 1 assumes a position on the hooks with the strands 2 thereof one over the other one inside and the other outside the hooks. After piercing the braid and while the cylinder needles are retracted, the part of the dual stranded braid outside the needle hooks is pushed over to the back of the needles by passing beneath the horizontal disc 13, which disc also functions to bring the strands 2 of the braid 1 side by side. From this position the machine operates in the manner previously described to draw thread loops between the strands of the braid and fasten the latter in the fabric.

The particular construction of the fabric embodying the plural stranded weft bars 1 may be varied without departing from the scope of the present invention. For instance fancy effects may be obtained by introducing at intervals different types of stitches and/or different kinds of stitch thread, and as an example a modified form of rib fabric is illustrated in Figs. 3 and 4

wherein, as compared with the fabric shown in Figs. 1 and 2, an additional thread course 26 is introduced at predetermined intervals and tuck stitches 27 are formed in alternate needle wales at said additional courses, said tuck stitches preferably occurring in the wales produced by the dial needles 7. If the additional course 26 with tuck stitches 27 is knitted immediately after introducing and anchoring each plural stranded weft bar 1, and the tuck stitches are made in the stitch wales appearing at the back of the fabric, i. e. on the dial needles, the effect produced is to shorten or tighten-up the cylinder needle stitches which are drawn through the weft braid 1 at the front of the fabric, thereby bunching-up the fabric over the anchored weft braids 1 and forming outstanding ribs or lines running weft-wise of the fabric as at 28 in Fig. 4. The thread introduced for making the additional stitch courses 26 with tuck stitches may be different from that used in making the remainder of the fabric. For example, the main fabric may be made of cotton or wool and the additional courses 26 of artificial silk thereby producing projecting lines 25 of artificial silk on the fabric face.

The braided weft 1 embodying the elastic strands 2 may be produced on any suitable braiding machine. For example, a machine may be employed wherein a plurality of spindles (e. g. six) traverse an endless track of double-loop or figure eight formation, a rubber strand being fed within each loop of the track. In Fig. 17 is shown a small portion of dual stranded braid illustrating how same may be constructed. The two strands 2 are each spirally wrapped with cotton or like covering threads 29, and the strands so wrapped are bound together side by side by binding threads 30 which pass alternately over one covered strand and beneath the other strands 40 in the manner of a double-loop or figure eight, the said binding threads intersecting each other between the two strands so as to space or divide said strands sufficiently for enabling a needle to pierce the braid between same. Where the covered or wrapped strands 2 are of rubber the spiral twist of the covering 29 of one strand is advantageously opposite to that of the other strand, as shown in Fig. 17, so that the finished braid is maintained flat.

50 This application is a division of application Serial No. 63,925, filed February 14, 1936, which eventuated into Patent 2,108,925.

I claim:—

1. A method of producing fabric on a rib knitting machine comprising the following sequential operations, namely:— producing knitted stitches on two sets of needles which draw loops in opposite directions, projecting needles of one set to a tucking height, simultaneously feeding below the hooks of said projected needles a plurality of weft threads or strands connected together side by side to form a composite bar, retracting said needles to cause the hooks thereof to pierce the plural stranded weft at a position between said strands, pressing said plural stranded weft over the needle hooks so as to bring one or more strands on one side and the remaining strand or strands on the opposite side of the 15 needles, projecting needles of both sets to clear the old loops thereon and feeding stitch thread thereto, retracting the needles of both sets to clear the old loops thereon and feeding stitch thread thereto, retracting the needles of both 20 sets to produce a new course of stitches and in so doing to cast off the plural stranded weft bar and draw stitch loops therethrough and subsequently operating the needles of both sets to produce a further stitch course. 25

2. A circular knitting machine embodying in combination a needle carrier with needles mounted to reciprocate therein, stitch thread feeding means, means for feeding under tension and at an adjustable speed a composite weft composed 30 of a plurality of elastic or other cores connected together side by side, a rotary wheel or disc having peripheral teeth or tricks adapted to be engaged by the needles and also having a peripheral channel functioning to guide the plural stranded 35 weft beneath the needle hooks, said channel cooperating with needles coacting with said wheel teeth or tricks to hold the composite weft up against said needles and locate said weft so that the points of the needle hooks pierce said weft 40 between the strands thereof, and means for pressing one or more of the strands of the weft so pierced over on to the back of the needles and maintain the remaining strand or strands on the front thereof. 45

3. A circular knitting machine according to claim 2 wherein said machine embodies two sets of needles functioning to draw stitch loops in opposite directions to produce rib fabric and wherein the composite weft is fed to one set of 50 needles, e. g. the cylinder needles, only.

HARRY AVERY RAYNOR.
